UNITED STATES PATENT OFFICE.

FRITZ KAEFERLE, OF HANOVER, GERMANY.

FLUID-PRESSURE REDUCING OR REGULATING APPARATUS.

No. 834,060.

Specification of Letters Patent.

Patented Oct. 23, 1906.

Application filed March 3, 1905. Serial No. 249,447.

To all whom it may concern:

Be it known that I, FRITZ KAEFERLE, manufacturer and engineer, a subject of the King of Prussia, German Emperor, residing at Hanover, Germany, have invented certain new and useful Improvements in Fluid-Pressure Reducing or Regulating Apparatus, of which the following is a specification.

This invention relates to improvements in apparatus for regulating or reducing the pressure of fluids—such as, for instance, steam.

Apparatus are known for this purpose in which a double-acting valve controlled by a float or weight floating on or in mercury is situated between the high-pressure chamber and the low-pressure chamber. One disadvantage of these apparatus lies in the fact that whenever the pressure of the fluid exceeds a certain limit, as will unavoidably occur, the mercury or a portion thereof is discharged from its normal receptacle, so that collectors, such as that described in the specification of United States Patent No. 671,069, granted to me on April 2, 1901, must be used to prevent the loss of mercury. The mercury-collector described in the patent referred to has, however, the disadvantage that it retains the discharged mercury until means have been operated to permit the mercury to flow back to its proper receptacle. If the apparatus to which the low-pressure fluid is supplied is situated at a considerable distance from the pressure-reducing device and if the said apparatus is, moreover, of such a kind that it has to be frequently started and stopped, considerable inconvenience is caused to the person in charge of the apparatus by the fact that each time the apparatus is stopped mercury is caused by the increase of pressure to flow into the mercury-collector, so that the latter must be emptied in the manner hereinbefore indicated.

In my previous patent, No. 682,085, granted to me on September 3, 1901, the discharge of the mercury which would occur by the momentum given to it on a sudden pressure is prevented by the use of a narrow bore in the tube; but this has the disadvantage that the return of the mercury is slower than is sometimes required.

The improved pressure-reducing apparatus to which the present invention relates is so designed that the use of a mercury-collector of the kind hereinbefore referred to is

obviated without reducing the bore of the tube.

The invention is illustrated in the annexed drawings, in which—

Figure 1 is a diagrammatic section of the improved device, and Fig. 2 a sectional detail view showing certain parts of the device in different relative positions.

H is the conduit leading from the high-pressure chamber, N the conduit leading to the low-pressure chamber, and D the valve controlled by the float P. The latter is connected to the valve D by means of a lever D' and suitable rods D² D³ and is situated in the chamber or cup G, which contains mercury. From the bottom of the chamber G a bent tube S leads to a receptacle U, situated at a higher level than the chamber G, and into the orifice of said tube S at the bottom of the chamber G there is loosely inserted the valve R, which is preferably of iron.

The action of the device is as follows: The valve R floats in the mercury and normally occupies the position shown in Fig. 2. When, however, the pressure below the valve D exceeds that pressure which it is desired to maintain in the low-pressure chamber, the level of the mercury in the chamber G is depressed by the pressure of the steam on the surface of the mercury and the float P sinks and partly or entirely closes the valve D. Owing to its buoyancy the valve R remains open while the mercury is being expelled from the chamber G toward the receptacle U; but should the mercury-level in the left-hand arm of the tube S sink to a sufficient extent to enable the valve R to reach and close the orifice in the bottom of the chamber G, as shown in Fig. 1, no more mercury can be expelled. Either when or before this position is reached the valve D will have been closed by the weight of the float P. When the excess of pressure below the valve D has disappeared, the "head" of mercury in the receptacle U causes the valve R to be reopened, so that mercury can flow back to the chamber G and lift the float P to the desired extent to again open the valve D.

It is obvious that the arrangement of the valve R, tube S, and receptacle U prevents the entire discharge of mercury from the controlling device and enables the mercury displaced by excess of pressure to return automatically to its normal position.

What I claim as my invention, and desire

to secure by Letters Patent of the United States, is—

In apparatus for reducing or controlling the pressure of fluids, the combination with 5 a pressure-chamber, a valve therein, a chamber containing mercury communicating with said pressure-chamber, a float in said mercury-chamber for operating the said valve aforesaid, an overflow-receptacle located at a 10 higher level than said mercury-containing chamber, and means of communication between said receptacle and the bottom of the

mercury-chamber, of a buoyant valve in the latter adapted to close said means of communication when the level of mercury in said chamber has fallen to a predetermined extent. 15

In witness whereof I have signed this specification in the presence of two witnesses.

FRITZ KAEFERLE.
